UNITED STATES PATENT OFFICE.

CHARLES HULTS, OF TORCH LAKE, MICHIGAN.

LOW-WATER ALARM AND INDICATOR FOR BOILERS.

SPECIFICATION forming part of Letters Patent No. 358,667, dated March 1, 1867.

Application filed November 6, 1886. Serial No. 218,154. (No model.)

To all whom it may concern:

Be it known that I, CHARLES HULTS, of Torch Lake, in the county of Antrim and State of Michigan, have invented a new and Improved Low-Water Alarm and Indicator for Boilers, of which the following is a full, clear, and exact description.

My invention relates to a low-water alarm and indicator for steam-boilers, and has for its object when the water in said boiler has fallen below a prescribed line to make known the fact instantly through the medium of a proper indicator located upon the boiler, together with an alarm from the whistle.

15 The invention consists in the construction and combination of the several parts, as will be hereinafter fully set forth, and pointed out in the claims.

Reference is to be had to the accompanying drawings, forming a part of this specification, in which similar letters of reference indicate corresponding parts in all the figures.

Figure 1 is a side elevation of a boiler, partly sectional, with my indicator and alarm attached, the water in said boiler being at a proper height; and Fig. 2 is also a side elevation similar to Fig. 1, illustrating the operation of the device, however, at low water. Fig. 3 is a detail view of a portion of the operating part. Fig. 4 shows the signal-board.

In the construction and application of my invention I provide a vertical frame, A, adapted for attachment at the top of a boiler, A', the said frame being preferably formed with an inner perpendicular bar, a, a short top horizontal bar, a', and an outwardly inclined rear bar, a''. Both of the said upright bars a and a'' are provided with a joint, b, in the same plane slightly above the boiler A', the purpose of which will be hereinafter stated, and about the center, upon the inside of the inclined bar a'', a lug, b', is formed integral therewith. The entire frame A above the said joint b may be made of a single piece of metal.

45 A stem, B, is entered through an aperture in the top of the frame A, and made to project downward into the boiler A' through a stuffing-box, B', screwed steam-tight in the casing of said boiler, the gland c of which is made to project through the said stuffing-

box below the same and form a bearing for the stem B, the lower projecting portion of said gland acting as a stay or brace therefor. The gland c is in turn made to serve as a stuffing-box for a second upper gland, c'. Thus, as it 55 were, a double stuffing-box is provided the said stem B.

The top of the stem B is furnished with a detachable hand-wheel, C, and the lower extremity thereof with a ball, d, which ball is 60 made to engage a central socket in the float D, the said float being adapted to rest upon the water contained in the boiler. Through the medium of this ball-and-socket connection the float D is enabled to move with the water 65 in the event the same is disturbed without straining the stem. To the offset b' of the inclined bar a'' one arm, e, of a toggle-lever, E, is pivoted, the other arm, e', thereof being projected beyond the perpendicular bar a of 70 the frame to a pivotal connection with the lower end of a spring, d', whose upper end is curved inward and attached to the said perpendicular bar a, near the top, upon its outer side. The arm e' of the toggle-lever E is also 75 pivoted by the same pivoted bolt, forming the connection with the said spring d' to a horizontal rod, F, which rod, at its other end, is entered through a casing, f, supported usually above the top of the boiler in front, having 80 formed upon its supports, near the bottom, a shelf, f'. The said rod F, in its passage through the casing f, is made to enter an aperture in a lettered board, f'', (shown in Fig. 4,) and sustain the same when the water is at a proper 85 height within the inclosure f, as illustrated in Fig. 1. The valve of the whistle G is also connected to the horizontal rod F by a suitable lever, g.

A horizontal arm, H, is attached to the inclined bar a'' of the frame A, provided with a set-screw, h, upon which the arm e of the toggle-lever E is adapted to rest, whereby the throw of the said lever is regulated. Another horizontal arm, K, is attached to the perpendicular bar a, and has centrally pivoted at the end thereof a pin, k, upon one end of which pin the arm e' of the toggle-lever rests. Above the said toggle-lever E in its normal position, and also above the pivoted pin k, a circular 90 95 100

plate, M, is adjustably secured to the stem B, the said plate being adapted at the proper time to engage one end of said pivoted pin and trip the said toggle-lever.

- 5 The operation is as follows: The throw of the toggle-levers having been adjusted by the set screw *h*, the circular plate M is secured in position upon stem B at such a distance above the toggle-lever E as will bring the two in line 10 when the float D is at a predetermined depth within the boiler. As the water diminishes, the float, resting upon the surface thereof, carries downward with it the stem B, and when the low-water line is reached the circular plate 15 M engages one end of the pivoted pin *h*, and, bearing down thereon, causes the outer end of said pin to bear against the under edge of the toggle-lever and raise the same at the center, whereupon through the contraction of the attached spring *d'* the said toggle-lever is carried upward, as shown in Fig. 2, and simultaneously through the connected rod F the whistle G is blown and the board *f'* released 20 to drop down upon the shelf *f''* and display 25 to the engineer or party in attendance the words "danger, water low in the boiler," or other equally expressive sentence. When it is desired to clean the brace or bearing for the stem and the stem itself, the bolts are with- 30 drawn at *b*, the connection with the toggle-lever E of the rod F broken, and the hand-wheel C unscrewed from the stem B. The frame and its connections are then readily removed. The gland *c* is now loosened and taken out and 35 cleaned and the stem drawn upward and likewise treated.

In transportation, to prevent the stem B from being strained, the said stem is drawn upward until the float comes in contact with 40 the brace or bearing *c*, and secured in position by the set-screw *m* in the top bar, *a'*, of the frame.

I purpose to construct the operative parts of my device of a non-corrosive metal, or in- 45 case the same in a suitable manner.

If desired, the double stuffing-box may be dispensed with, and a single box employed instead, and the float, instead of being attached with a ball-and-socket joint to the stem, may be fastened rigidly thereto. The ball-joint is, 50 however, preferred. The rod F may be also substituted by a wire attached to a pin passing through the casing *f* to an engagement with the indicator *f''*.

Having thus described my invention, what 55 I claim as new, and desire to secure by Letters Patent, is—

1. In a boiler-alarm, the combination, with the float-rod carrying an adjustable plate, M, and toggle-levers connected at one end with a 60 signal device and a spring, and said spring, of the arm K, and the pin *h*, pivoted on said arm, substantially as shown and described, and for the purposes set forth.

2. The combination, with the boiler A' and 65 a jointed frame, A, attached thereto, toggle-levers E, pivoted at one end to said frame and at the other to a spring, F, and signal devices, the said spring F, and horizontal arm K, having centrally pivoted thereto a pin, *k*, of the 70 float-rod B, provided with a hand-wheel, C, and adjustable circular plate M, and a float, D, attached thereto by a ball-and-socket joint, substantially as shown and described.

3. The combination, with the boiler A' and 75 a jointed frame secured thereto, provided with an arm, H, carrying an adjusting-screw, *h*, an arm, K, having pivoted centrally to its end a pin, *k*, the toggle-levers E, connected at one end to said frame and at the other to a spring, 80 F, and alarm devices, and the said spring F, of a float-rod, B, provided with an adjustable circular plate, M, and a float attached thereto by a ball-and-socket joint, substantially as shown and described, whereby notice is given 85 when the water in said boiler is low, as set forth.

CHARLES HULTS.
